(57) **CLAIM**

The ornamental design of an end piece of a pneumatic patient circuit, as shown and described.

DESCRIPTION

FIG. 1 is a front perspective view of an end piece of a pneumatic patient circuit;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is another perspective view thereof shown in an environment of use.

The broken lines in the drawings illustrate portions of the end piece of an pneumatic patient circuit that form no part of the claimed design. All other broken lines shown in FIG. 8 are included for the purpose of illustrating environmental subject matter and form no part of the claimed design.
